UNITED STATES PATENT OFFICE.

JENNINGS COMRIE, OF GLOVERSVILLE, NEW YORK.

GLOVE.

SPECIFICATION forming part of Letters Patent No. 395,954, dated January 8, 1889.

Application filed January 17, 1888. Serial No. 261,037. (No model.)

To all whom it may concern:

Be it known that I, JENNINGS COMRIE, a citizen of the United States, residing at Gloversville, in the county of Fulton and State of New York, have invented new and useful Improvements in Gloves, of which the following is a specification.

My invention relates to improvements in gloves, with the object of improving the attachment of the thumb to the hand of the glove, whereby the liability of a detachment of the same is reduced.

It is my object, further, to improve the hand of the glove, the fingers of the same, and the attachment of the fingers to the hand, whereby the seams will come in positions where they will be subjected to the least possible strain and wear, thus preventing in a great measure the ripping of seams which so frequently occurs.

With these objects in view I provide the sides of the thumb-opening with integral ears, under which the inner edges of the thumb are arranged, and I then stitch the edges of the thumb to the hand of the glove, and also stitch the edges of the ears to the thumb. Thus a double thickness of material is disposed at the points of the greatest strain, and two lines of stitching are formed, which mutually support and strengthen each other.

In the ordinary practice the seams in the fingers of the glove are arranged at the sides, and the bending of the fingers of the wearer causes a direct lateral strain upon the stitches, which soon breaks the latter; also the rubbing of the fingers together causes the seams to be rapidly worn, and the strength of the stitches is thus impaired. I arrange the seams on the backs or outer sides of the fingers, thereby protecting them from wear and causing the strain upon the stitches when the hand of the wearer is closed to be less direct.

The invention is described more in detail hereinafter in connection with the accompanying drawings, wherein—

Figure 1 is a view of the back or outer side of a glove. Fig. 2 is a view of the palm or inside of the same. Fig. 3 is a plan view of

the blank from which the hand is formed. Fig. 4 is a similar view of the blank from which the thumb is formed. Fig. 5 is a similar view of the blank from which the two intermediate fingers and the back gore are formed. Fig. 6 shows three modified forms of thumb-openings.

Referring by letter to the drawings, A designates the hand of the glove, which consists of the main fold A', forming the palm of the hand, and the back flaps, a a, which fold over to form portions of the back of the hand, and B C designate, respectively, the first and fourth fingers, which are formed integral with the hand, and consist of the main folds B' and C', respectively, the back folds, b' c', of which are of the same width as the back flaps, and have openings b² and c² therein and the tongues b c on the inner sides of the said main folds to fit in the openings b' c'. These openings b' and c' extend outward as far as the centers of the backs of the fingers B C, and therefore the seams which secure the edges of the tongues b c in the openings come at the centers of the backs of the fingers. The edges of the flaps a a are not sewed together; but a slightly wedge-shaped gore, D, is inserted between them, which is provided with a V-shaped notch in its lower end. The lower end of the gore does not extend to the lower end of the main fold A' or the palm of the glove.

E F represent, respectively, the intermediate fingers, which are located between the fingers B C, and they consist, respectively, of the main folds e f and the back flaps, e' e' f' f'. The upper ends of these back flaps are provided with extensions or tongues e³ e³ f² f², which are beveled at their upper ends. The adjacent edges of the folds e' e' and their extensions or tongues e² e² are stitched together, and the adjacent edges of the folds f' f' and their extensions or tongues f² f² are similarly connected, thereby forming the fingers E and F. The free edges of the adjacent inner tongues e² f² are stitched together, and the free edges of the outer tongues e² f² are stitched to the free portion of the back flaps, a a, below the end of the gore. It will be seen that when the extensions e² e² f² f² are con-

connected together their combined upper edges form a wedge-shaped point, which fits in the **V**-shaped notch at the lower end of the gore. The upper edges of the hand of the glove are strengthened by a flap, E', which is stitched to the upper edges of the main fold, back flaps, and gore, and then turned outward and stitched to the outside of the same. The thumb-opening F' is oval in shape, and has a wedge-shaped point, G, at its lower end projecting up into the opening.

H H represent ears which are arranged at the sides of the opening, and also project thereinto. It will be understood that the said point G and the ears H H are formed integral with the main or palm fold A'.

K represents the thumb-blank, which is of the ordinary shape and fits in the opening F' under the point G and the ears H. The edge of the thumb is stitched to the hand of the glove around the opening, and the edges of the point and the ears are also stitched to the sides of the thumb. It will be seen that the seams are not arranged in the lines of bending between the thumb and the hand, and therefore they are not liable to rip.

There are no seams between the fingers of the glove, and therefore the unavoidable rubbing together of the fingers does not affect the seams. The gore at the back of the hand may be omitted, if preferred; but the glove is more easily made and a better fit is obtained with this addition, and, further, in cutting out the blanks more of the material can be utilized when the gore is formed separate.

In the drawings I show the thumb-opening provided with two ears and a wedge-shaped point; but the said point may be omitted. I desire to show, however, that the said point may be used with advantage in connection with the above-mentioned ears, and that all may be formed from a single blank and cut from the opening to which the thumb is to be applied.

I am aware that gloves are made with one ear, and I therefore do not claim this construction; but I hold that two ears, as shown, are of advantage, and especially when used in combination with the above-mentioned point G.

That the advantage in providing the rear side of the glove with a gore is thoroughly appreciated is evidenced by the fact that this construction is not new; but in the herein-described improved glove the gore is made much shorter than the back of the hand of the glove, and the intermediate fingers are provided on their rear sides with tongues, which extend up between the adjacent exposed edges of the back flaps, a a, and are attached at their outer edges to the said exposed edges and at their upper ends to the lower end of the gore.

There are various advantages gained by this construction: The joint between the intermediate fingers and the hand of the glove

is strengthened, for the reason that the strain in bending the hand does not come transversely on the seam, but to a certain extent longitudinally, and, furthermore, the intermediate fingers are enabled to be arranged with their seams at the back.

Having thus described my invention, I claim—

1. In a glove, the hand having the oval opening F' therein, the ears H on opposite sides of the opening and formed integral with the hand, and the thumb arranged at its inner edges under the ears and stitched to the palm around the opening F, the said ears being stitched to the sides of the thumb, substantially as specified.

2. In a glove, the hand comprising the main fold A' and the back flaps, a a, in combination with the gore D, inserted between the adjacent edges of the said back flaps and terminating above their lower ends, the said gore being provided in its lower end with a **V**-shaped notch, the outer fingers at the lower end of the hand, and the intermediate fingers, E F, attached together and to the hand, and having tongues e² f² on their upper ends stitched together to form a projection or extension which is secured between the exposed lower ends of the flaps a a, and is provided with a wedge-shaped upper end fitting in the **V**-shaped notch in the lower end of the gore, substantially as specified.

3. In a glove, the hand A, comprising the main fold A' and the back flaps, a a, the gore D, arranged between the adjacent edges of the flaps a a and terminating above their lower ends, and the fingers B C, integral with the hand A, in combination with the fingers E F, arranged between the fingers B C, and comprising the main folds e f, the back flaps, e' e' and f' f', stitched, respectively, together at their adjacent edges, and the tongues e² e² and f² f² on the upper ends of the said back flaps, respectively stitched together to form extensions, which extensions are stitched together at their adjacent edges, stitched at their upper ends to the lower end of the gore, and stitched at their outer edges to the exposed edges of the flaps a a, substantially as specified.

4. In a glove, the combination of the hand having a thumb-opening, F', the integral wedge-shaped point G at the lower end of the opening F', the integral ears H H on the sides of the opening F', and the thumb stitched in the said opening and having the ears H and the point G stitched thereto, substantially as and for the purpose hereinbefore specified.

5. The herein-described glove, comprising the hand A, consisting of the main fold A' and the back flaps, a a, on its edges, the gore D, stitched between the opposing edges of the flaps a a, the outer fingers, B C, integral with the lower end of the hand and consisting of the main folds B' C', the back folds, b' c', on the outer edges of the main folds, having re-

cesses b^2 c^2 therein, the tongues b c on the inner edges of the main folds, fitting within the said recesses and stitched to their edges, the intermediate fingers, E F, provided with extensions or tongues on their upper ends, stitched to the lower end of the gore, and fitting between the lower ends of the flaps a a , and the thumb stitched in a suitable opening in the hand, substantially as specified.

In testimony that I claim the foregoing as my own I have hereto affixed my signature in presence of two witnesses.

JENNINGS COMRIE.
